his Attorney.

UNITED STATES PATENT OFFICE

EDUARD LANKEs, OF MUNICH, GERMANY

PRINTING SURFACE AND PROCESS OF PRODUCING THE SAME

Application filed June 23, 1928, Serial No. 287,880, and in Germany April 11, 1927.

The invention relates to a printing surface and improvements in the process of producing the same, by impressing a picture on the side of a sheet having its surface coated with chalk or prepared clay and washing or etching away those portions of the surface which are not covered by the impression. This has heretofore been generally done by coating both sides of the sheet of paper or the like, and also impressing both sides, which is a difficult and expensive operation, the sheet being useless, if the two impressions are not exactly in register. It has also been proposed to coat and impress only one side, which reduces the labour and expense, and produces a thinner sheet, suitable for use in rotary and platen presses of substantial power, but it is found that the solution of chloride of lime used for washing or etching, to produce the relief, penetrates the sheet and destroys it.

My invention consists substantially of a relief printing surface formed by a sheet, coated on one side only with a chalk or clay preparation. The back of the sheet is protected from the action of the solvent or etching liquid by impregnation or by application of a protective coating. For this purpose I may use a hardener, such as formaldehyde, or an inorganic hardening salt, or the like, with animal glue or casein as binding agent. The chalk or clay is preferably applied in the form of thin successive layers.

This treatment of the back of the sheet tends also to prevent the curling of the sheet.

The invention is illustrated in the accompanying drawing which shows a transverse section of the improved plate. In the drawing, *a* denotes a sheet of paper material or the like having one of its surfaces provided with a coating *b* of chalk or clay preparation and its opposite surface provided with a coating *c* resistant to any liquid capable of removing the substance of the coating *b*.

The etching of a plate such as that shown in the drawing is effected as follows: The entire plate is immersed in the etching fluid so that not only the chalk or clay coated side but also the rear side is subject to the action of the etching fluid. The chalk or clay coated sur-

face is etched by the fluid and, unless the rear side of the plate were protected, it also would be attacked by the fluid, making the paper brittle and interfering with proper registry. As shown in the drawing, the rear side of the plate is provided with the resistant coating *c*, and under these conditions when the plate as a whole is immersed in the etching fluid and repeatedly turned therein as is usually done, the chalk or clay treated surface is properly etched while the opposite surface which is protected by the resist *c* is unaffected by the etching fluid, so that destruction of the paper and rolling up of the plate are prevented, and no trouble with registration is encountered.

What I claim is:—

1. Mechanical relief printing surface, consisting of a sheet of paper coated on one side only with a chalk or clay preparation relief, characterized by the fact that the uncoated side of the sheet is protected from the action of the solvent or etching liquid by a protected coating which remains permanently in place and prevents the sheet from curling.

2. Process of producing a printing surface, consisting in coating one side only of a sheet of paper with prepared chalk or clay, applying to the uncoated side of the sheet a material which remains permanently in place and renders the sheet resistant to a washing or etching liquid capable of removing the chalk or clay and which material also prevents the sheet from curling, impressing a picture on the side of the sheet coated with chalk or clay and washing or etching away the chalk or clay not covered by the impression of the picture.

3. A mechanical relief printing surface as claimed in claim 1, in which the protective coating consists of a hardener and animal glue as a binding agent.

4. A mechanical relief printing surface as claimed in claim 1, in which the protective coating consists of formaldehyde and animal glue.

In testimony whereof I hereunto affix my signature.

EDUARD LANKEs.
